UNITED STATES PATENT OFFICE.

JOHN J. MILLIN, OF BROOKLYN, NEW YORK.

FLYING-MACHINE.

1,171,865.

Specification of Letters Patent. Patented Feb. 15, 1916.

Application filed April 24, 1911. Serial No. 622,981.

To all whom it may concern:

Be it known that I, JOHN J. MILLIN, a citizen of the United States, and a resident of the borough of Brooklyn, in the county of Kings and State of New York, have invented certain new and useful Improvements in Flying-Machines, of which the following is a specification.

This invention relates to that class of flying machines which are supported by the reaction of the air under one or more aeroplanes. It differs from the type in general use at this time, in the fact that the present machines depend for their support on the compression of the air under their aeroplanes, by placing the said aeroplanes at a small angle of incidence with the horizontal plane, whereas in my invention the angle of incidence of the aeroplanes is immaterial and in fact the planes may have a reverse angle from that now used. The lifting effect in this invention is obtained by rarefying the air immediately above its aeroplanes, by the means hereinafter described.

Some of the objects of my invention are to provide means for rarefying the air above the planes as above stated, and to provide means both automatic and manually controlled, to increase or decrease the degree of rarefaction above any or all of the planes, in order to maintain the lateral and longitudinal equilibrium of the machine, to bank the same when turning to the right or left and for ascending and descending.

In the drawings, Figure 1 represents a partial top plan view of the invention with portions broken away, Fig. 2 shows a partial section of Fig. 1 on the line 2—2, Fig. 3 is a front view of the machine, Fig. 4 is a rear view of the machine, Fig. 5 is an enlarged fragmentary section of Fig. 1 on the line 5—5, Fig. 6 is a section of Fig. 5 on the line 6—6, Fig. 7 is an enlarged fragmentary portion of Fig. 1, Fig. 8 is a section of Fig. 7 on the line 8—8, Fig. 9 is an enlarged fragmentary portion of Fig. 2, Fig. 10 is a right hand side view of Fig. 9, Fig. 11 is a section of Fig. 6 on the line 11—11, Fig. 12 is a left hand side view of Fig. 11, Fig. 13 is an enlarged partial section of Fig. 2 on the line 13—13, Fig. 14 is a section of Fig. 13 on the line 14—14, Fig. 15 is a section of Fig. 13 on the line 15—15, Fig. 16 is an enlarged plan view of the front portion of the machine, Fig. 17 shows a right hand side view of Fig. 16, Fig. 18 represents a partial en-

larged section of Fig. 1 on the line 18—18, Fig. 19 represents a fragmentary plan view of a modified aeroplane with its appurtenances, and Fig. 20 shows a section of Fig. 19 on the line 20—20.

The invention as exemplified in the drawings, comprises a frame with the upper longitudinal member 20, the lower longitudinal members 21, 22, upright braces 23, connecting the members 20 and 21, 22, and cross braces 24 that connect the members 21, 22. An inclined front brace frame 25 connects the front ends of the members 20, 21, 22. An upper horizontal converging member 26 of the rudder frame of the machine extends from the rear end of the member 20, and a lower horizontal converging member 27 of the rudder frame extends from the members 21, 22. Vertical braces 28 of the rudder frame connect the members 26 and 27, and a rudder bracket 29 connects the ends of said members 26, 27. A wheel frame 30 extends from the members 21, 22, and has formed on its ends the forks 31, on which latter are journaled the wheels 39. A V-shaped wheel bracket 40 is also connected to the members 21, 22, and has formed on its lower end the fork 41, in which latter is journaled the wheel 42. A front bell crank with the horizontal arms 43 and the vertical arm 44 is journaled on one of the cross-braces 24. A second front bell crank with the horizontal arms 45 and the vertical arm 46, is journaled on an adjacent cross brace 24. The arm 46 has a slot 47, in which is located a screw 48, the ends of which latter are journaled in said arm 46, and which carries in threaded engagement therewith the block 49, with the pivots 50, and also carries at its upper end the grooved pulley 51. The arms 44 and 46 are pivotally connected at their lower ends by the front connecting rod 52. A rear bell crank with horizontal arms 60 and the vertical arm 61 is journaled on one of the cross braces 24. A second rear bell-crank with the horizontal arms 62 and the vertical arm 63 is journaled on an adjacent cross brace 24. The vertical arms 61 and 63 are pivotally connected at their lower ends by the rear connecting rod 64. A central connecting rod 65 has one end pivotally connected to the arm 61, and the other end engages the pivots 50 of the block 49.

A shaft 70 is journaled in the ends of the horizontal arms 43 of the front bell-crank and the said shaft has formed therewith

the forked ends 71, 72, in which latter are respectively pivoted the suspension rods 73, 74. A shaft 80 similar to 70 is journaled in the ends of the horizontal arms 45 of the 5 second front bell-crank and the said shaft, has formed therewith the forked ends 81, 82 in which are respectively pivoted the suspension rods 83, 84. A shaft 90 similar to 70 is journaled in the ends of the horizontal 10 arms 60, of the rear bell-crank, and the said shaft has formed therewith the forked ends 91, 92 in which are respectively pivoted the suspension rods 93, 94. A shaft 100 similar to 90 is journaled in the ends of the horizontal 15 arms 62 of the second rear bell-crank and the said shaft has formed therewith the forked ends 101, 102 in which are respectively pivoted the suspension rods 103, 104. The suspension rods 73 and 83 are connected 20 at their lower portions by the horizontal brace 108, and at their upper portions by the horizontal brace 109. Diagonal guys 110, 111 connect the suspension rods 73, 83. The suspension rods 74, 84 are connected 25 by the braces 112, similar to 108 and a brace not shown similar to 109. Diagonal guys 113, 114 connect the rods 74 and 84. The suspension rods 93 and 103 are connected 30 at their lower portions by the horizontal brace 118 and at their upper portions by the horizontal brace 119. Diagonal guys 120, 121 connect the suspension rods 93, 103. The suspension rods 94, 104 are connected by the brace 122 similar to 118, 35 and a brace not shown similar to 119. Diagonal guys 123, 124 connect the rods 94, 104. The suspension rods 73, 74 are connected at their upper ends by a link 125 and beyond said link the said rods are continued in normally horizontal planes to 40 constitute the main ribs 126 and 127 of the front aeroplanes of the machine. The rods 83, 84 are connected at their upper ends by a link 128 similar to 125 and beyond the latter 45 link the said rods are continued in normally horizontal planes to constitute the main ribs 129, 130 of the said aeroplanes. A plurality of longitudinal ribs 132 are supported on the main ribs 126 and 129. A covering 133 is secured to the top and bottom 50 faces of the longitudinal ribs 132, and forms with the latter and the main ribs 126 and 129 the front left hand aeroplane designated generally by 135. An oscillating shaft 136 is journaled in the front ends of the longitudinal ribs 132, and has fastened thereto the forked arm 127, in which is pivoted the trunion block 138. To the latter is pivoted the upper end of the adjusting rod 140. To 55 the oscillating shaft 136 are fastened a plurality of preferably curved arms 141 which have fastened thereto a covering 143 that constitutes therewith a deflector designated generally by 145. Guy wires 146 connect the main ribs 126, 129 with the lower por- 60 tions of the suspension rods 73, 83. The main ribs 127, 130 are connected by a plurality of longitudinal ribs 149 similar to 132. A covering 150 is secured to the top and bottom faces of the longitudinal ribs 70 65 149 and form with the latter and with the main ribs 127, 130 the front right hand aeroplane designated generally by 155. An oscillating shaft 156 similar to 136 is journaled in the front ends of the longitudinal 70 ribs 149, and has fastened thereto the forked arm 157 similar to 137 and in which is pivoted the trunion block 158 similar to 138. To the latter is pivoted the upper end of the adjusting rod 160 similar to 140. To the 75 oscillating shaft 156 are fastened a plurality of preferably curved arms 161 similar to 141, which have fastened thereto a covering 163 similar to 143 that constitutes therewith a deflector designated generally by 165. Guy 80 wires 166 connect the main ribs 127, 130 with the lower portions of the suspension rods 74, 84. The suspension rods 93, 94 are connected at their upper ends by a link 170 and beyond said link the said rods are continued in normally horizontal planes to 85 form main ribs 172, 173 of the rear aeroplanes of the machine. The rods 103 and 104 are connected at their upper ends by a link 175 similar to 170, and beyond the latter link, the said rods are continued in normally horizontal planes to form the main ribs 179, 180 of the said rear aeroplanes. A plurality of longitudinal ribs 182 are supported on the main ribs 172, 179. A 90 covering 183 is secured to the top and bottom faces of the longitudinal ribs 182 and form with the latter and main ribs 172, 179 the rear left hand aeroplane designated generally by 185. 95

An oscillating shaft 186 is journaled in the front ends of the longitudinal ribs 182 and has fastened thereto the forked arm 187 in which is pivoted the trunion block 188. To the latter is pivoted the upper end of the adjusting rod 190. To the oscillating shaft 186 are fastened a plurality of preferably curved arms 191, which have fastened thereto a covering 193 that constitutes therewith a deflector designated generally by 195. Guy wires 196 connect the main ribs 172, 179 with the lower portions of the suspension rods 93, 103. The main ribs 173, 180 are also connected by a plurality of longitudinal ribs 202 similar to 182. A 100 covering 203 is secured to the top and bottom faces of the longitudinal ribs 202 and form with the latter and with the main ribs 173, 180, the rear right hand aeroplane 105 designated generally by 205.

An oscillating shaft 206 similar to 186 is journaled in the front ends of the longitudinal ribs 202 and has fastened thereto the forked arm 207 similar to 187, in which is pivoted the trunion block 208 similar 110

125

130

to 188. To the latter is pivoted the upper end of the adjusting rod 210 similar to 190. To the oscillating shaft 206 are fastened a plurality of preferably curved arms 211 5 similar to 191, which have fastened thereto a covering 213 similar to 193, that constitutes therewith a deflector designated generally by 215. Guy wires 216 connect the main ribs 173, 180, with the lower portions 10 of the suspension rods 94, 104. Adjacent to the front ends of the lower longitudinal members 21, 22 are respectively fastened the journal brackets 220, 221 in which are respectively supported the oscillating shafts 222, 223. At the outer ends of the shafts 222, 223 are respectively fastened the forked arms 224 and 225. A trunnion block 228 is pivoted in the arm 224 and has pivotally connected thereto the lower end of the adjusting rod 140. A trunnion block 229 similar to 228 is pivoted in the arm 225 and has pivotally connected thereto the lower end of the adjusting rod 160. At the inner ends 15 of the oscillating shafts 222, 223, are respectively fastened the levers 230, 231. Adjacent to the rear ends of the longitudinal members 21, 22 are respectively fastened the journal brackets 235, 236 in which are respectively supported the oscillating shafts 237, 238. At the outer ends of the said 20 shafts are fastened the forked arms 239, 240. A trunnion block 241 is pivoted in the arm 239 and has pivotally connected thereto the lower end of the adjusting rod 190. A trunnion block 242 similar to 241 is pivoted 25 in the arm 240 and has pivotally connected thereto the lower end of the adjusting rod 210. At the inner ends of the oscillating shafts 237, 238 are fastened the levers 245 and 246. Wires 250, 251 connect respectively the upper ends of the levers 230, 245 and 231, 246. Wires 252, 253 respectively connect the lower ends of said levers. Brackets 260, 261, are respectively fastened to the 30 front ends of the lower longitudinal members 21, 22 and carry the connecting brace 262. An oscillating forked bracket 263 is supported on the brace 262 and carries the steering column 264 with the steering wheel 265. A grooved pulley 266 is fastened to the steering column between the arms of the forked bracket 263, and at the lower end of said steering column is fastened the crank arm 267 with the crank pin 268. A pin 270, 35 extends from the bracket 263 and supports a double bell-crank having the arms 271, 272 and forked arm 273. Links 274 and 275 respectively connect the arms 271, 272 with the lower ends of levers 230, 231. In the rudder bracket 29 is supported the rudder shaft 280 which carries the rudder 40 60. A collar 282 is fastened adjacent to the upper end of the shaft 280, which latter at its lower end carries the pulley 283. Brackets 284 extending from the member 27

have journaled thereon the guide pulleys 285 and 286. A steering rope 287 connects the pulleys 286 and 283 being guided over the guide pulleys 285, 286.

To the lower longitudinal member 21 and 70 the second cross brace 24 from the front end of the machine is fastened a bracket 300, which supports a journal pin 301. On the latter is journaled the sleeve 302 that has formed therewith at its upper end the pulley 303 and at its lower end the pulley 304. The pulley 303 is connected to the pulley 51 by means of the belt 305. At the front of the lower longitudinal member 21 is fastened a journal bracket 310 that has journaled therein an adjusting shaft 311. The said shaft has fastened thereto at its upper end the adjusting hand wheel 312, and at its lower end has secured thereto or formed therewith the pulley 313. A belt 314 connects the pulley 313 with the pulley 304.

A propelling engine 318 is connected up with the longitudinal members 20, 21 and 22, and has secured to its shaft the propeller 320. A seat 321 is located at the front end 90 of the machine.

In the modified aeroplane shown in Figs. 19 and 20, 325, 326 are the main ribs on which are supported a plurality of longitudinal ribs 327. A covering 328 is secured 95 to the top and bottom faces of the longitudinal ribs 327 and forms with the latter and with the main ribs 325, 326 the aeroplane designated generally by 330. An oscillating shaft 331 is journaled in the front ends of 100 the longitudinal ribs 327. Fastened to the oscillating shaft 331 in different angular positions are a plurality of preferably curved arms 332. The oscillating shaft 331 has also fastened thereto the crank arm 333, 105 and the adjusting rod 334 is connected to the crank arm 333. In the outer ends of the curved arms 332 is journaled a second oscillating shaft 335. Fastened to the second oscillating shaft in various angular positions are a plurality of second curved arms 110 336. A crank arm 337 is fastened to the oscillating shaft 335 and a second crank arm 338 is fastened to the oscillating shaft 331. A link 339 connects the ends of the crank arms 337, 338. A covering 340 is connected 115 to the curved arms 332 and a covering not shown similar to 340 is connected to the curved arms 336. The curved arms 332, 336 with their coverings and other appurtenances constitute an adjustable balanced deflector in which the upward and downward thrusts against the respective surfaces of the deflector, balance one another.

To use the invention, the operator seats 125 himself in the machine, the engine is started and the machine is moved forward by the thrust of the propeller. When the machine has attained the requisite velocity for flying, the operator pulls the steering wheel 265 to 130

ward himself, thereby swinging the steering column 264, the oscillating bracket 263 and the double bell-crank which is supported on the latter, around the connecting brace 262. Through the agency of the links 274, 275, which are connected to the arms 271, 272, of the double bell-crank, the lower ends of the levers 230, 231 are swung forward and they in turn pull forward the lower ends of the levers 245, 246, through the agency of the wires 252, 253. By these means the oscillating shafts 222, 223 and 237, 238 are partially rotated thereby swinging upwardly their respective forked arms 224, 225 and 239, 240. The adjusting rods 140, 160, 190, 210 being connected at their lower ends to the aforesaid forked arms, are moved upwardly and the said rods being connected at their upper ends to the forked arms 137, 157, 187 and 207 respectively cause a partial rotation of the oscillating shafts 136, 156, 186 and 206, thereby raising the deflectors 145, 165, 195 and 215. The air coming in contact with the said deflectors is deflected upwardly and after leaving the deflectors does not return to its normal density immediately above the aeroplanes of the machine. The air in passing over the deflectors may be likened to a body of water flowing over a dam. In the latter case, the water after passing over the edge of the dam descends in a parabolic curve. The space bounded by the parabolic path of the water, the face of the dam and the distance from the foot of the dam to the point at which the water strikes the earth, contains only air and a certain amount of spray.

The deflectors in this invention are equivalent to the dam in the above illustration and the air in passing over said deflectors descends in parabolic curves and the spaces between these curved paths of the air and the upper faces of the aeroplanes are filled with rarefied air or in other words, partial vacuums exist immediately above the aeroplanes. The height of the deflectors and the other proportions of the aeroplanes are such that the amount of unbalanced pressure against the under surfaces of the aeroplanes will be sufficient to lift the machine from the ground, when it has attained a predetermined forward velocity. The steering wheel having been pulled toward the operator and the deflectors raised the requisite height, the machine will rise from the ground. To lower the machine the steering wheel is pushed forward and by means of the immediate connections heretofore described the deflectors are lowered, the vacuum above the aeroplanes is decreased and the machine as a consequence descends.

The various deflector arms on each of the oscillating shafts 136, 156, 186 and 206 being located in different angular positions relative to the upper faces of their respective

aeroplanes, the perpendicular distances of the upper edges of each deflector from the upper face of its accompanying aeroplane varies and decreases uniformly from the inner longitudinal edge of each aeroplane 70 to the outer end thereof. It is evident, therefore, that when the oscillating shafts of the deflectors are partially turned, the proportionate change in the height of each deflector is greatest at the outer end of each aeroplane and uniformly decreases, reaching its minimum at the said inner edge of each aeroplane.

The front aeroplanes 135, 155 of the machine having extending downwardly therefrom their respective suspension rods 73, 83 and 74, 84, and the said suspension rods being connected to the forked ends of the shafts 70, 80 which are journaled in the horizontal arms 43, 45 of the front bell-cranks, it is evident that when said bell-cranks are swung about their axes, the front aeroplanes will move up and down in unison and their longitudinal axes will always remain parallel with the longitudinal axis of the machine. The two front bell-cranks are forced to move in unison by reason of the connecting rod 52. The same results are obtained with the rear aeroplanes by reason of their connections to the rear bell-cranks and the fact that the rear bell-cranks are forced to move in unison by the connecting rod 64. The vertical arms 46 and 61 of the front and rear bell-cranks, as already described, are connected by the central connecting rod 65, the location of the forward end of which rod can be varied by means of the screw 48.

The pressure which it is necessary to obtain against the under surface of each aeroplane to sustain the machine in a horizontal position in the air, having been determined, the forward end of the connecting rod 65 is set by means of the screw 48 at such a position on the arm 46, that the upward pressures against the front aeroplanes, acting through the bell-crank and connecting rod 65 will just balance the upward pressures against the rear aeroplanes. It is evident, therefore, that when the front and rear aeroplanes are subjected to their pre-determined pressures there will be no up or down movement of the aeroplanes. Should the pressures on the front aeroplanes at any time exceed the predetermined amount there would immediately be an unbalanced pull exerted on the connecting rod 65, by the front aeroplanes. This would cause the front aeroplanes to rise and pull the connecting rod 65 forward, thus lowering the rear aeroplanes. The adjusting rods 140 and 160 being stationary they would cause the deflectors on the front aeroplanes to lower with respect to their accompanying aeroplanes as the aeroplanes rise, thus re- 130

ducing the pressures under the front aeroplanes. The adjusting rods 190, 210 also being stationary, they would cause the deflectors on the rear aeroplanes to rise with respect to their accompanying aeroplanes as the rear aeroplanes are lowered. This raising of the front aeroplanes and lowering of the rear aeroplanes would continue until the excess pressures had been properly proportioned between the front and rear aeroplanes. The machine would then start to rise in a horizontal position to a higher elevation. Should the operator not desire this he simply pushes the steering wheel forward thus lowering all of the deflectors and bringing the total pressure under the aeroplanes back to the normal amount. Should the pressure on the rear aeroplanes become excessive it is evident that the reverse actions from the above will take place. The automatic longitudinal equilibrium of the machine is thus assured.

Each of the aeroplanes being pivotally connected at the lower ends of their respective suspension rods, to elements connected with the frame of the machine, it is evident that unless the pressures on the opposite aeroplanes of either the front or rear pair are equal, or the pressures multiplied by the horizontal distance from the centers of application to the pivotal points of their respective aeroplanes are equal, the opposed aeroplanes will swing about their pivotal points toward the side of the machine where the least pressure exists. It follows therefore that should the pressure on the left hand front aeroplane become excessive, both front aeroplanes will swing toward the right hand side of the machine. When this occurs, the adjusting rod 140 pulls the deflector of the left hand aeroplane downwardly through the agency of the elements before described, thus decreasing the pressure on the left hand aeroplane and the adjusting rod 160 pushes the deflector of the right hand aeroplane upwardly, thus increasing the pressure on the right hand aeroplane. When the deflector of the front left hand aeroplane moves downwardly, the proportion of decrease in pressure is greatest at the outer edge of the aeroplane and uniformly decreases reaching its minimum at the inner edge of the aeroplane, therefore, at the same time that the pressure under the left aeroplane is being decreased the center of application of the pressure is being moved in toward the center of the machine. On the other hand, as the pressure on the right hand aeroplane is being increased its center of application is being moved away from the center of the machine. This action of the aeroplanes will continue until the pressures under the opposite aeroplanes have become such that the turning movements around the pivotal

points of the opposite aeroplanes have become equal. The aeroplanes will then remain in this position until the cause of the excess pressure has been removed, at which time they will again return to their normal positions.

Should the pressure under the right hand front aeroplane become excessive the reverse action takes place. The same results with respect to the lateral equilibrium of the rear pair of aeroplanes are obtained by their similar elements. By this means the automatic lateral equilibrium of the machine results.

It will be readily seen that both the automatic, lateral and longitudinal adjustments may be made at the same time. To turn the machine to the right or left, the operator turns the steering wheel 265 in the desired direction, and by means of the pulley 266, the steering rope 287, and the pulley 283, the rudder is properly located. In turning the machine to the right or left it is essential to bank it to prevent the machine from being thrown from its path by the action of centrifugal force. This banking effect is obtained at the same time that the machine is being turned, by means of the crank pin 268 turning the double bell-crank on its axis, thus raising the deflectors on the aeroplanes on the outer side of the curve and lowering the deflectors on the inner aeroplanes. This causes the aeroplanes to swing toward the inner side of the curve thus banking the machine. As before described, the machine can be raised or lowered while maintaining a horizontal position by simply moving the steering wheel 265 backward or forward. The machine may, however, ascend or descend at an angle with the horizontal plane. When so doing it is evident that the horizontal distances of the center of gravity of the machine from the front and rear aeroplanes is altered, thus changing the pressures on said front and rear aeroplanes. To accomplish this the operator turns the adjusting hand wheel 312 and through the agency of the pulley 313, the belt 314, the pulley 303, the belt 305 and the pulley 51, the screw 48 is rotated thus moving the end of the connecting rod 65 to a new position on the arm 46. Should the operator wish to descend at an angle, he moves the end of the connecting rod in toward the axis of the arm 46. This action causes the pressure on the front aeroplanes to exert a greater pull on the connecting rod 65 than is exerted by the pressure on the rear aeroplanes. The front aeroplanes will then move upward and decrease their pressures and the rear aeroplanes will move downward and increase their pressures. This action continues until the pressures on the front and rear aeroplanes exert an equal pull on the connecting rod 65. The

rear aeroplanes are now sustaining a greater part of the weight of the machine than when in the horizontal position. Therefore the front end of the machine has been lowered the desired amount and the machine will travel downward at that angle. Should it be desirous to ascend at an angle the end of the connecting rod 65 is moved out on the arm 46, thus causing the machine to rise 10 at the desired angle.

The automatic longitudinal adjustment of the front and rear aeroplanes will maintain the machine at any desired angle in the same way as it acts for horizontal travel.

15 The rear edges of the aeroplanes are shown as having a slight upward curve. This is done to cause the air on the under side of the aeroplanes to give them a forward thrust as it leaves their rear edges, 20 and thus compensate to some extent for the head resistance of the deflectors.

Having described my invention, what I claim and desire to secure by Letters Patent is:

25 1. In a flying machine the combination of an aeroplane and automatic adjustable means to produce a partial vacuum adjacent to the upper surface of the aeroplane.

30 2. In a flying machine the combination of an aeroplane, means to alter the angular position of the aeroplane with respect to the transverse axis of the machine and adjustable means to produce partial vacuums adjacent to the upper surface of the aeroplane.

35 3. In a flying machine the combination of a pair of laterally opposed aeroplanes, means to alter the angular positions of the aeroplanes with respect to the transverse 40 axis of the machine and adjustable means to produce partial vacuums adjacent to the upper surfaces of the aeroplanes, and to decrease the amount of vacuum on the ascending plane and increase the amount of vacuum on the descending plane.

45 4. In a flying machine the combination of an aeroplane, means to locate the aeroplane in different positions parallel to each other and adjustable means to produce partial vacuums adjacent to the upper surface of the aeroplane.

50 5. In a flying machine the combination of an aeroplane, automatic means to locate the aeroplane in different positions parallel to each other and adjustable means to produce partial vacuums adjacent to the upper surface of the aeroplane.

55 6. In a flying machine the combination of an aeroplane and adjustable means connected to the aeroplane to produce a partial vacuum adjacent to the upper surface of the aeroplane when the machine is moving and also to simultaneously vary the amount of vacuum and move the center of unbalanced 60 pressure against the under side of the aero-

plane to new positions relative to the lateral margins of the aeroplane without altering the angular relation of the aeroplane or any portion thereof with the line of flight of the machine.

70 7. In a flying machine the combination of a plurality of aeroplanes and adjustable means connected to said aeroplanes to produce partial vacuums adjacent to the upper surfaces thereof when the machine is in motion and also to simultaneously vary the amounts of vacuum and move the centers of unbalanced pressure against the under sides of the aeroplanes to new positions relative to the lateral margins of the aeroplanes, 75 without altering the angular relation of the aeroplanes or any portions thereof with the line of flight of the machine.

75 8. In a flying machine the combination of an aeroplane and a deflector adjustably connected to the aeroplane, the angle of inclination of said deflector with the upper surface of the aeroplane gradually decreasing from a maximum at the inner to a minimum at the outer lateral margin thereof.

80 9. In a flying machine the combination of a plurality of aeroplanes and a deflector adjustably connected to each aeroplane in proximity to its front edge and extending above the upper surface thereof, the angle of inclination of said deflector with respect to the upper surface of the aeroplane, gradually decreasing from a maximum at the inner to a minimum at the outer lateral margin thereof.

85 10. In a flying machine the combination of an aeroplane, a deflector adjustably connected thereto, the angle of inclination of said deflector with the upper surface of the aeroplane gradually decreasing from a maximum at the inner to a minimum at the outer lateral margin thereof and means to alter the angles of inclination of the deflector with respect to the upper surface of the aeroplane.

90 11. In a flying machine the combination of a plurality of aeroplanes, a deflector adjustably connected to each aeroplane in proximity to the front edge thereof and projecting above the upper surface of the same, the angle of inclination of each deflector with respect to the upper surface of its accompanying aeroplane, gradually decreasing from a maximum at the inner to a minimum at the outer lateral margin thereof, 95 and means to alter the angles of inclination of each deflector with respect to the upper surface of its aeroplane.

100 12. In a flying machine the combination of an aeroplane, an oscillating shaft supported in the aeroplane, deflector arms extending from said shaft in different angular positions with respect to the upper surface of the aeroplane, the angularity of said positions decreasing from a maximum at the 105

inner to a minimum at the outer lateral margin of the aeroplane, a covering for the deflector arms forming therewith a deflector, a crank arm connected to the oscillating shaft and an adjusting rod connected to said crank arm.

13. In a flying machine the combination of a plurality of aeroplanes, an oscillating shaft supported in each aeroplane, deflector arms extending from each shaft in different angular positions with respect to the upper surface of their accompanying aeroplanes, the angularity of said positions decreasing from a maximum at the inner to a minimum at the outer lateral margin of each aeroplane, a covering over each set of deflector arms forming therewith a deflector, a crank arm connected to each oscillating shaft and an adjusting rod connected to each arm.

14. In a flying machine, a pair of laterally opposed aeroplanes pivotally connected to the frame of the machine and to each other, the axes of said pivotal connections being parallel to the longitudinal axis of the machine; and to each other; a deflector adjustably connected to each aeroplane, means to simultaneously increase or decrease the angle of inclination of both deflectors or to increase one and decrease the other relatively to their accompanying aeroplanes.

15. In a flying machine a pair of laterally opposed aeroplanes located in front of the center of gravity of the machine, a pair of laterally opposed aeroplanes located to the rear of the said center of gravity, means to permit the laterally opposed aeroplanes to oscillate in unison about axes parallel to the longitudinal axis of the machine and to each other, means to permit the longitudinally opposed pairs of aeroplanes to move simultaneously in opposite directions up or down with respect to the frame of the machine, without altering their angular relation with the line of flight of the machine, other means to cause the upward movement of one pair of aeroplanes to move the other pair downward with respect to the frame of the machine, a deflector adjustably connected to each aeroplane, means to simultaneously decrease the angle of inclination of the deflector on the rising aeroplane, and increase the angle of inclination of the deflector on the lowering aeroplane, when the laterally opposed aeroplanes oscillate about their respective longitudinal axes, and means to decrease the angles of inclination of the deflectors on the upwardly moving pair of aeroplanes and to increase the angles of inclination of the deflectors on the downwardly moving pair of aeroplanes when the opposed pairs of aeroplanes are moving in opposite directions.

16. In a flying machine a pair of front aeroplanes and a pair of rear aeroplanes, both pairs of aeroplanes located above the

center of gravity of the machine and capable of up and down movements with respect to the frame of the machine, an adjustable connection between the front and rear pairs of aeroplanes through which the upward pressure against each pair of aeroplanes is transmitted and reacts on and balances the pressure against the opposite pair, manually controlled means to adjust the connection between the front and rear pairs of aeroplanes and alter the ratio of the balancing pressures of said aeroplanes and cause the machine to incline longitudinally and change the ratio of the horizontal distances from the center of gravity to the front and rear aeroplanes.

17. In a flying machine the combination of a frame, bell cranks journaled in the frame on axes parallel to the transverse axis of the machine, shafts journaled in the normally horizontal arms of the bell cranks, the axes of said shafts being parallel to the axes of the bell cranks, suspension rods pivoted to the ends of said shafts on axes parallel to the longitudinal axis of the machine, an aeroplane connected up with said suspension rods and a connecting rod connecting the normally vertical arms of the bell cranks.

18. In a flying machine the combination of a frame, bell cranks journaled in the frame on axes parallel to the transverse axis of the machine, shafts journaled in the normally horizontal arms of the bell cranks, the axes of said shafts being parallel to the axes of the bell cranks, a connecting rod connecting the normally vertical arms of the bell cranks, suspension rods pivotally connected to the ends of the shafts on axes parallel to the longitudinal axis of the machine, links connecting the laterally opposed suspension rods at the upper portions thereof and an aeroplane connected up with each set of laterally opposed suspension rods.

19. In a flying machine, the combination of a frame, bell cranks journaled in the frame in front of the center of gravity of the machine and on axes parallel to the transverse axes of the machine, bell cranks journaled in the frame in the rear of the center of gravity of the machine on axes parallel to the transverse axis of the machine, shafts journaled in the normally horizontal arms of the front bell cranks on axes parallel to the axes of the bell cranks, similar shafts journaled in the same manner in the rear bell cranks, suspension rods pivoted to the ends of the shafts in the front bell cranks on axes parallel to the longitudinal axis of the machine, similar suspension rods pivoted in the same manner to the ends of the shafts in the rear bell cranks, links connecting the laterally opposed suspension rods, an aeroplane connected up with each set of laterally opposed suspension rods, a

connecting rod connecting the normally vertical arms of the front bell cranks, a similar connecting rod connecting the normally vertical arms of the rear bell cranks, and an 5 adjustable connecting rod connecting the front bell cranks with the rear bell cranks.

20. In a flying machine the combination of a plurality of laterally opposed pairs of aeroplanes, a deflector connected to each 10 aeroplane, means to alter the angle of inclination of each deflector with respect to the upper surface of its accompanying aeroplane, means to permit the laterally opposed aeroplanes to oscillate in unison around axes 15 parallel to the longitudinal axes of the machine, means to permit the longitudinally opposed pairs of aeroplanes to move simultaneously in opposite directions up or down with respect to the body of the machine, 20 means to turn the machine to the right or left, and means to swing the laterally opposed aeroplanes around their longitudinal axes at the same time that the machine is being turned to the right or left, to cause 25 the aeroplanes on the outer side of the curved path of the machine to rise and the inner aeroplanes to lower, to bank the ma-

chine and oppose the action of centrifugal force.

21. In a flying machine, the combination 30 of an aeroplane, an oscillating shaft journaled in the aeroplane, a plurality of preferably curved arms connected to the said oscillating shaft, a crank arm supported on the oscillating shaft, an adjusting rod connected to said crank arm, a second crank arm connected to the oscillating shaft, a second oscillating shaft journaled in the front 35 ends of the curved arms, a plurality of second curved arms fastened to the second oscillating shaft, a crank arm connected to the second oscillating shaft, a link connecting 40 said crank arm with the second crank arm on the first oscillating shaft and a covering connected to the curved arms to form 45 therewith a deflector.

Signed at the borough of Manhattan in the county of New York and State of New York, 1911.
